US0D1016560S

(12) **United States Design Patent** (10) **Patent No.:** **US D1,016,560 S**
(45) **Date of Patent:** **** Mar. 5, 2024**

(54) **BEVERAGE CONTAINER**

- (71) Applicant: **BruMate, Inc.**, Dover, DE (US)
(72) Inventor: **Dylan M. Jacob**, Denver, CO (US)
(73) Assignee: **BruMate, Inc.**, Denver, CO (US)

(**) Term: **15 Years**

(21) Appl. No.: **29/756,343**

(22) Filed: **Oct. 27, 2020**

Related U.S. Application Data

- (62) Division of application No. 29/675,424, filed on Jan. 1, 2019, now Pat. No. Des. 899,854, which is a division of application No. 29/594,947, filed on Feb. 23, 2017, now Pat. No. Des. 836,983.

CLAIM

The ornamental design for a beverage container, as shown and described.

DESCRIPTION

FIG. 1 is a front view of a beverage container, showing my new design;

FIG. 2 is a rear view of FIG. 1;

FIG. 3 is a right side view of FIG. 1;

FIG. 4 is a left side view of FIG. 1;

FIG. 5 is a top view of FIG. 1;

FIG. 6 is a bottom view of FIG. 1; and,

FIG. 7 is a perspective view of FIG. 1.

The dot-dash broken lines depict boundaries of the claimed design. The even-length broken lines in the drawings depict portions of the beverage container that forms no part of the claimed design.

1 Claim, 7 Drawing Sheets
